ATTORNEY.

UNITED STATES PATENT OFFICE

CARL L. ROSE, OF KANSAS CITY, MISSOURI

EGG TONGS

Application filed March 14, 1929. Serial No. 346,922.

The present invention relates to egg tongs, and aims to provide a novel and improved appliance of this type which will be adapted for greater convenience in the handling of 5 eggs as well as with greater safety on account of the fragile nature of the egg shell.

Accordingly the primary object of the invention is to devise a resiliently constructed tongs appliance adapted for both 10 yieldingly gripping contact with the eggs and also for a yielding action of the handles carrying the egg-gripping elements for avoiding any undue pressure upon the eggs in the gripping function.

15 It is further sought to provide an extremely simple and inexpensive construction of a thoroughly practical as well as efficient character for the desired purpose.

With these general objects in view, the 20 invention will now be described by reference to the accompanying drawing wherein is illustrated one form of embodiment of the proposed features of improvement, after which novel features thereof will be particularly set forth and defined in the appended claim.

In the drawing—

Figure 1 is a plan view illustrating an 25 egg tongs appliance constructed in accordance with the present invention;

Figure 2 is a side view of the device, in open position; and

Figure 3 is a perspective view of the 30 appliance closed and in gripping engagement with an egg.

Referring now to the said drawing in detail, this shows my improved appliance as constructed of a single piece of suitable wire material, preferably of a somewhat 35 springy or resilient character and of non-corrosive properties, and adapted to be bent at a point midway between its ends to form a coil 5 acting as a resilient hinge-like element connecting the handle members. Each 40 handle member comprises a series of oppositely turned bends 6 in the wire adjacent to the coil 5, and a straight portion 7—that portion of the wire having the bends 6 constituting the hand-grip element, and the 45 portion 7 forming a resilient arm connect-

ing the hand-grip portion with the corresponding egg-gripping element. Preferably the bends 6 in the two hand-grip elements are relatively staggered, as represented in Figure 1, for greater comfort to 55 the hand as well as lending a balancing effect in the hand-gripping action.

At the outer end of the straight portion 7 of each handle member the wire is appropriately bent to provide an egg-gripping 60 element comprising a pair of split, yielding or expandible coils, namely, a relatively larger coil 8 and a somewhat smaller coil 9, with a wire connecting portion 10 between said coils. The larger coil is open 65 at the end of the handle portion 7, where the wire connecting portion 10 is bent both backwardly and outwardly to provide both for opening or splitting said coil and also for spacing the two coils slightly apart (as 70 shown in Figures 2 and 3); and the wire terminating in the coil 9 of course provides a split or opening therein which also comes opposite the end of the arm or handle portion 7. The combined shape and contour of the two coils approximates an oval cup-shape design, and the yielding nature 75 of the material, as well as the open or split character of the coils, adapts the same to conform yieldingly to one of the sides of 80 an egg 12 as illustrated in Figure 3.

In the preferred construction, the ends of the coils 9 may also be slightly bent or curved inwardly, toward the coils 8, for conforming still more to the contour of the 85 end portions of the egg, as indicated at 9' in Figures 2 and 3.

By means of this construction, it is apparent that a tongs device is provided in which the egg-gripping elements are of a 90 completely yielding and flexible character adapted, upon contacting engagement with the egg, to conform automatically and accurately to the outside contour of the egg, without any undue or crushing pressure at 95 any point of the shell. This action is rendered all the more yielding and resilient by the springy nature of the handle members, since the same resilient wire material is used throughout, and in the actual con- 100

struction the length of the handles, including the straight portion 7, is so chosen as to provide an ample degree of resiliency to insure that no injurious pressure can possibly be exerted upon the egg, such as would tend to break the shell. The handle portions 6 are very convenient and comfortable for hand-gripping purposes, the thumb of the hand engaging one of the forward bends 10 at either side of the device according to which hand is used for gripping the appliance.

It is thus apparent that a very practical and efficient construction has been devised for the embodiment of the invention. In addition to its completely flexible and resili- 15 ent character, insuring no damage being done to the egg, it enables the eggs to be handled very quickly, the egg being gripped 20 by means of the gripping coils and nesting therein almost instantly because of the oval cup-shaped design, and moreover is held therein securely by virtue of the gripping elements completely embracing the egg on 25 all sides or practically surrounding the same.

The device is particularly useful in the cooking of eggs, by boiling, since it enables the eggs to be submerged in the water after 30 it has already been brought to the boiling point and without requiring the egg to be dropped into the vessel at the risk of cracking the shell. After the boiling operation, the egg is as conveniently and safely re- 35 moved from the water, and if desired can be cooled while retained in the tongs by either dipping in cold water or holding it under a stream of cold water,—the skeleton or open-work character of the gripping coils 40 being such as to expedite the cooling effect by exposing practically the entire surface of the shell.

Being constructed from a single piece of wire material, it is also apparent that the 45 device is not only extremely simple but is also adapted to be manufactured at a minimum cost for its production.

While I have herein illustrated and de- 50 scribed what I now regard as the preferred form of embodiment of my improvements I desire to reserve the right to make all such changes or modifications as may fairly fall within the scope of the appended claim.

Having described my invention, what I 55 claim and desire to secure by Letters-Pat- ent, is:

An egg tongs device comprising a pair of handle members, and an egg-gripping element carried by each of said handle mem- 60 bers, each of said elements comprising a single piece of wire bent to form a pair of split expandible coils, a relatively large coil secured to one end of the corresponding handle member and a relatively smaller coil formed by a backward bend of the

free end portion of the wire, and thereby forming oval cup elements adapted for gripping the opposite sides of an egg and yield- 70 ingly conforming to the exterior thereof, the major axis of each of said cup elements being substantially at right angles to the corresponding handle member.

In witness whereof I hereunto affix my signature.
